UNITED STATES PATENT OFFICE.

ROBERT W. MARTLAND, JR., OF BERKELEY, CALIFORNIA, ASSIGNOR TO PACIFIC RADIATOR, OF OAKLAND, CALIFORNIA, A PARTNERSHIP CONSISTING OF ROBERT W. MARTLAND AND ROBERT W. MARTLAND, JR.

LEAF HOLDER FOR BOOKS.

Application filed February 29, 1928. Serial No. 257,862.

This invention relates to a device adapted to be fitted to books for retaining the leaves of the same in open position.

It is the principal object of the present invention to provide a simple and inexpensive device adapted to be mounted adjacent the binding of leaves in a book and normally disposed in an unobstructing position but capable of manipulation to engage the leaves of the book when disposed in an open position to retain the book open.

In carrying out the invention into practice I provide a hooked member rotatably and reciprocably mounted adjacent the binding of the book. This member is normally disposed in an unobstructing position overlying the leaves but is capable of being extended and aligned with leaves arranged in open position and engaged with the leaves to retain them in open position.

One form which the invention may assume is exemplified in the following description and illustrated by way of example in the accompanying drawings, in which:

25 Fig. 1 is a perspective view of a book with the covers open showing my improved device arranged on the book.

30 Fig. 2 is a similar view of the book with a portion of the leaves disposed in open position with my improved device engaging the leaves to retain them in said position.

35 Referring more particularly to the accompanying drawings, 10 indicates a book having covers 11 between which a plurality of pages 12 are disposed. These pages 12 are bound together along one edge as indicated by the numeral 14. The manner in which these leaves are bound together is of no particular importance but in the present instance

40 I have shown a loose leaf binding including an upper plate 15 through which binding elements 16 project. In the present instance the binding of the leaves is arranged at right angles to the fold of the covers. This is not necessary, however, as my invention may be applied to books constructed in a manner other than that illustrated.

Arranged on the plate 15 is a guide 17 arranged parallel to the bound edges of the

leaves. Slidably and rotatably disposed in 50 this guide 17 is a member 18 which may be made of comparatively stiff wire if desired. The outer end of this member 18 is hooked as at 19. The inner end is slightly offset as at 20, so that the member cannot be entirely 55 disengaged from the guide 17.

As shown in Fig. 1 the member is capable of being disposed in a position overlying the leaves and flatly against the same, so that it will in no manner obstruct the use of the hook. 60

When it is desired to maintain the leaves of the book open, the member 18 is extended outwardly so that the pages when opened will clear the hooked end of the member. The member is then slightly revolved so as to align 65 its hooked portion with the opened leaves and then moved inwardly to engage the leaves as shown in Fig. 2. Such engagement will retain the leaves in open position.

When it is desired to release the leaves, it 70 is only necessary to disengage the hooked end 19 therefrom, permit the leaves to assume their normal position and then return the member 18 to the position disclosed in Fig. 1.

It is obvious from the foregoing that the 75 device here disclosed while simple and inexpensive in construction, provides effective means for retaining the leaves of the book in open position.

While I have shown the preferred form 80 of my invention, it is to be understood that various changes may be made in its construction by those skilled in the art without departing from the spirit of the invention, as defined in the appended claims. 85

Having thus described my invention, what I claim and desire to secure by Letters Patent is:

1. In combination with a plurality of leaves bound together at one edge, guide means 90 adjacent the bound edge, a member rotatably and reciprocably connected with said guide means to reciprocate in a direction parallel to the bound edge and to rotate in a plane at right angles thereto, said member having leaf 95 engaging means adapted to be engaged with opened leaves by manipulation of the member to retain said leaves in open position, said

member and means being capable of being disposed flatly overlying the leaves when the leaves are in closed position.

2. In combination with a plurality of leaves bound together at one edge, of a guide mounted adjacent said bound edge and arranged parallel thereto, a member having an elongated portion rotatably and reciprocably

mounted in said guide, the outer end of said member being hooked whereby the member may be disposed flatly overlying the leaves or be extended and rotated to align the hook with opened leaves and then engaged with the leaves to retain them in open position. ¹⁰
